UNITED STATES PATENT OFFICE.

EDUARD LEISSNER, OF NEW YORK, N. Y.

DESIGN FOR WALL-PAPER.

SPECIFICATION forming part of Design No. 13,155, dated August 8, 1882.

Application filed June 30, 1882. Term of patent 3½ years.

To all whom it may concern:

Be it known that I, EDUARD LEISSNER, of New York, in the county and State of New York, have invented a new and original Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

The figure B is a rosette with radial outwardly-extending lines. The figure A consists of a series of curving arms running from a circular center. E resembles a rosette with angular leaves. C somewhat resembles a spider's web, while D bears some resemblance to a circular saw, and the figure F is a rosette with angular projections around it. Circles *a* are placed in the radial lines that project from said rosettes. *b* are hexagonal figures, alternating

with said circles, as shown. The space between these various figures is filled up by a vine bearing numerous pointed leaves.

I claim—

1. The design for wall-paper, consisting of the figure A, substantially as shown.
2. The design for wall-paper, consisting of the figure B, substantially as shown.
3. The design for wall-paper, consisting of the figure D, substantially as shown.
4. The design for wall-paper, consisting of the figure C, substantially as shown.
5. The design for wall-paper, consisting of the figure F, substantially as shown.
6. The design for wall-paper, consisting of the figure E, substantially as shown.
7. The design for wall-paper, consisting of the figures A B C D E F *a b*, substantially as shown.

EDUARD LEISSNER.
